US00D962444S

(12) **United States Design Patent** (10) **Patent No.:** **US D962,444 S**
(45) **Date of Patent:** **** Aug. 30, 2022**

(54) **SCANNER**

- (71) Applicant: **WELCH ALLYN, INC.**, Skaneateles Falls, NY (US)
- (72) Inventors: **Carlos Suarez**, Skaneateles Falls, NY (US); **Erol Ozcelik**, Skaneateles Falls, NY (US); **Ynjiun Wang**, Skaneateles Falls, NY (US); **Timothy R. Fitch**, Skaneateles Falls, NY (US); **Thomas A. Myers**, Skaneateles Falls, NY (US)
- (73) Assignee: **WELCH ALLYN, INC.**, Skaneateles Falls, NY (US)

(**) Term: **15 Years**

(21) Appl. No.: **29/782,077**

(22) Filed: **May 4, 2021**

Related U.S. Application Data

- (63) Continuation of application No. 29/694,179, filed on Jun. 7, 2019, now Pat. No. Des. 921,899.
- (51) **LOC (13) Cl.** **24-01**

(57) **CLAIM**

We claim the ornamental design for a scanner, as shown and described.

DESCRIPTION

FIG. 1 is a perspective view of a scanner showing our new design;
FIG. 2 is another perspective view thereof;
FIG. 3 is a front elevation view thereof;
FIG. 4 is a rear elevation view thereof;
FIG. 5 is a right side elevation view thereof;
FIG. 6 is a left side elevation view thereof;
FIG. 7 is a top plan view thereof;
FIG. 8 is a bottom plan view thereof;
FIG. 9 is another perspective view thereof, shown in a position of use attached to an adjustable pedestal; and,
FIG. 10 is a right side view thereof.
The broken lines depicting an adjustable pedestal in FIGS. 9 and 10 represent environmental subject matter and form no part of the claimed design; and the remaining broken lines depict portions of the scanner that form no part of the claimed design.

1 Claim, 9 Drawing Sheets
